DOOR AND THE LIKE

Filed Aug. 20, 1928

UNITED STATES PATENT OFFICE

STEPHEN S. THOMAS, OF LEBANON, OHIO

DOOR AND THE LIKE

Application filed August 20, 1928. Serial No. 300,856.

This invention has to do with improvements in doors for stoves and the like. The invention relates especially to improvements in the means for sealing the edge portions 5 of such doors in an air tight and steam tight manner so as to be able to retain the vapors under a reasonable amount of pressure. The invention relates especially to improvements such as the foregoing incorporated in doors 10 for ovens of the fireless cooker type and also the type in which a certain amount of heat is initially generated and is then retained in the oven structure by the presence of a suitable heat insulating material.

15 More particularly the invention relates to improvements in the means for sealing the edge portions of the taper or wedge doors which are drawn to a wedging seat.

One object of the invention is to provide a 20 seal of the foregoing nature and which is so formed that it can be readily applied to doors of a type of oven construction already extensively in use. Another object of the invention is to provide an arrangement which 25 will be very cheap to manufacture and which can be produced in considerable length and then cut up into sections of the proper length for use in different locations.

Other objects and uses of the invention will 30 appear from a detailed description of the same which consists in the features of construction and combinations of parts herein-after described and claimed.

In the drawing: 35 Figure 1 shows a front elevation of an oven door having applied thereto a seal embodying the features of the present invention, a portion of the door being broken away so as to show the interior construction thereof;

40 Fig. 2 shows a fragmentary horizontal section on the line 2-2 of Fig. 1 looking in the direction of the arrows but on enlarged scale; and

45 Fig. 3 shows a vertical fragmentary section of the upper corner of a door structure and seal embodying the features of the present invention.

For purposes of convenience I have herein 50 illustrated the features of the present invention as applied to an oven of the general type

disclosed in my co-pending application for Letters Patent on improvements in stoves and the like, Serial No. 223,674 which was filed October 3, 1927. In so doing however, it will be understood that I do not intend to thereby 55 limit the application or usefulness of the features of the invention except as I may do so in the claims.

Bearing the foregoing in mind the door structure as a whole is designated by the numeral 4. It includes the inner sheet metal pan 5 together with a front cover plate 6, the latter preferably reinforced by an outside plate 7. The peripheral portion of the pan 5 is flared outwardly on a tip 8 and then has 60 its extreme edge returned straight out as shown at 9 to receive the edge portion 10 of the plate 6 which is folded over said portion 9. Suitable heat insulating material 11 is 65 placed within the pan before the cover 6 is 70 secured thereon.

The flared portion 8 of the door sets into a companion jamb member 12 which has a slightly greater flare. The inner edge of the member 12 is returned on a relatively 75 sharp but rounded angle on a reverse curve as shown at 13 so as to establish an outwardly facing socket 14 which leaves a slight clearance from the inner edge of the door pan 5. The wall 15 of the oven has its front edge 80 rounded outwardly and lapped over the portion 13, but is not carried over far enough to interfere with the placing of the seal gasket presently to be described.

Suitable latches 16 and 17 are provided for 85 locking and also for drawing the door home in a tight manner.

The sealing gasket is shown in detail in Figs. 2 and 3. Generally speaking it comprises a tubular strip or strips of asbestos cloth or similar material 18, and a wire 19 is extended lengthwise through each of these tubular strips. The tubular strips are of such size that when set into place as shown in Fig. 2 they substantially occupy the portion 14 and when the door is forced home said gaskets are compressed into an oblong or elliptical cross section as illustrated in Fig. 2.

The gaskets are conveniently held in place by the wires 19, for which purpose said wires 100

may be extended beyond the tubular gaskets themselves and then extended through holes in the sheet 12 and folded over as shown at 20 and 21 in Fig. 3.

5 It will be understood that the gaskets may be readily set into place or removed by slightly deflecting the wires 19, but these wires are stiff enough to normally retain the gaskets in place when they have once been 10 inserted.

10 While I have herein shown and described only a single embodiment of the features of my present invention, still I do not intend to limit myself thereto except as I may do so 15 in the claims.

I claim:

1. The combination with a rectangular door jamb having a relatively deep outwardly tapered sealing surface, terminating at its 20 inner edge in an outwardly facing concave recess encircling the inner edge of said jamb, and a relatively thick door for said jamb, said door having its edge portion also tapered to conform to the taper of the door jamb, 25 said inner edge of the door terminating in an inwardly reaching encircling projection working into the concave recess of the door jamb, of means for sealing said inner edge of the door with respect to the jamb comprising a sectional gasket composed of 30 straight sections of asbestos tubing with reinforcing wires extending through them and beyond their ends, said tubing sections being seated into the concave recesses of the jamb 35 in position to receive the edge of the door, and the projecting ends of the wires extending through openings in the corners of the jamb, substantially as described.

2. The combination with a door opening 40 having straight peripheral portions, said opening tapering outwardly to present door jamb surfaces, there being concave outwardly facing grooves at the inner edges of said surfaces, and a door for said opening having 45 companion wedging edge surfaces, of means for sealing the inner edge of the door with respect to the inner edge portion of the jamb when the door is closed, comprising straight gaskets of asbestos corresponding to straight 50 sides of the door jamb, said gaskets being seated into the outwardly facing concave portions aforesaid, each gasket including a wire extending through it and projecting beyond the ends of the asbestos and engaged with 55 suitable holes in the adjoining door jamb faces, substantially as described.

3. The combination with a rectangular door jamb having a relatively deep outwardly tapered sealing surface terminating at its 60 inner edge in an outwardly facing concave recess at the inner edge of said jamb, and a relatively thick door for said jamb, said door having its edge portion also tapered to conform to the taper of the door jamb, said 65 inner edge of the door terminating in an in-

wardly reaching encircling projection extending into the concave recesses of the door jamb, of means for sealing said inner edge of the door with respect to the jamb comprising a gasket composed of asbestos tubing and reenforcing wire extending therethrough, said tubing being seated into the concave recess of the jamb in position to receive the edge of the door, and means for securing said tubing and wire in place within said recess, substantially as described. 70 75

4. The combination with a rectangular door jamb having a relatively deep outwardly tapering sealing surface terminating at its inner edge in an outwardly facing concave 80 recess at the inner edge of said jamb, and a relatively thick door for said jamb, said door having its edge portion also tapered to conform to the taper of the door jamb, said inner edge of the door terminating in an inwardly reaching projection extending into the concave recesses of the door jamb, of means for sealing said inner edge of the door with respect to the jamb comprising a gasket composed of asbestos tubing, said tubing 85 being seated into the concave recess of the jamb in position to receive the edge of the door, and means for securing said tubing in place within said recess, substantially as described. 90 95
